CHARLES D. YOUNG, OF ALTOONA, PENNSYLVANIA.

TRACK CONSTRUCTION.

1,199,143.

Specification of Letters Patent. Patented Sept. 26, 1916.

Application filed July 6, 1915. Serial No. 38,272.

To all whom it may concern:

Be it known that I, CHARLES D. YOUNG, a citizen of the United States, residing at Altoona, in the county of Blair and State of Pennsylvania, have invented certain new and useful Improvements in Track Construction, of which the following is a specification.

The invention relates to track construction and particularly to the proportioning of the splice bars. It has for its primary objects; the provision of an improved type of splice bar which shall be equal to or greater in strength than the type of splice bar now in use and much lighter in weight; and the provision of an improved type of splice bar which does not require that the opposing ends of the bar should come over and be supported by a pair of ties positioned for that purpose, as is necessary under the present practice, so that a great saving of time is effected due to the fact that no care need be exercised in locating the joints at particular points with respect to the ties. One embodiment of the invention is illustrated in the accompanying drawings, wherein—

Figure 1 is an end view of the rail and the splice bars employed therewith, Fig. 2 is a side elevation of the rail joint, and Fig. 3 is a side elevation on a reduced scale showing the relation of the rail joints to the ties.

Heretofore it has been the practice to arrange the joints of the rails so that they always come midway between adjacent ties with the ends of the splice bars over the adjacent ties, the two splice bars thus constituting in effect a bridge between the two ties. These splice bars as heretofore used were made relatively longer and less stiff or resistant to bending than the bars employed in the practice of my invention, the ratio of the length of the bars to their lower section modulus (or to their upper section modulus) being in all cases greater than two.

For example, under the old practice, with a standard 100 pound rail (100 pounds per yard), having a tie spacing of twenty inches from center to center, the splice bars usually employed, if of the plain type of uniform cross section from end to end, were 24 inches long and had a section modulus below the neutral axis of about 7.72, and above the neutral axis of 7.28, so that the ratio of length to section modulus was over three. With the same rail and with the Bonzano type of splice bar of non-uniform cross section, having the downward extension at

its central portion, the length of bar was 26½ inches, with a section modulus below the neutral axis of 9.45 and above the neutral axis of 11.73, so that the ratio of length to either section modulus was between two and three.

By "section modulus" as above used, is meant the ratio of the moment of inertia of the cross section to the distance of the extreme fiber of the cross section from the neutral axis, represented by the well known formula $\frac{I}{v}$. The section modulus multiplied

by the stress per unit area equals the moment of bending. The section moduli thus serve as a basis of comparison of the relative degree strength of bars of varying cross sections. As the lower parts of rail and splice bar sections are subject to tensional strains, and yield more readily to stress than the upper portions which are under compression, the lower section moduli form a better basis of comparison in considering the stiffness of various bars than the upper section moduli.

I have found that if a proper attachment is made between the rails and splice bars, the length of the splice bars can be very materially reduced without in the least decreasing the resistance of the rail to bending at the joint, and without decreasing the strength of the joint. Also that if the bars be of proper stiffness, the joints can be located without regard to the location of the ties, it being entirely unnecessary that the bars be supported at the ends upon adjacent ties. For instance with the 100 pound standard rail I can use a plain splice bar only 15 inches long instead of 24 inches, having a lower section modulus of 12.5 and an upper section modulus of 9.19, so that the ratio of length to lower section modulus is only about 1.2 instead of between two and four as in the old practice. This means that I can secure a joint of the same or greater strength than that of the old practice and of much less weight, and a joint which can be used without regard to the location of the ties, thus involving a great saving of time in laying and relaying the track.

Referring to the drawings: 1 is the rail; 2 are the splice bars; 3 are the bolt holes; and 5 are the ties. The rail illustrated in Figs. 1 and 2 is a standard 100 pound rail, drawn half size, $x-x$ indicating the neutral axis of the cross section of the rail and $y-y$ that of the splice bars. The proportions of

the cross sections of the rail and splice-bars are accurately shown in Fig. 1, which is the preferred embodiment of my invention as used with the standard 100 pound rail. It will of course be understood that this merely illustrates the principle of the invention, as the length of the splice bar and its proportions might be modified within certain limits even with a 100 pound rail, and variations in the size and shape of the rail would call for variations in the length and other proportions of the splice bars. The exact dimensions of the particular embodiment illustrated are set forth below.

15 A=15''
 B=3 $\frac{1}{4}$ ''
 C=1 $\frac{1}{2}$ ''
 D=5 $\frac{5}{6}$ 44''
 E=5''
 F=2 $\frac{1}{8}$ ''
 G=20''
 20

It will be noted from Fig. 3 that the joints of the rail are located without regard to the spacing of the ties, and that the length of the splice bars, 15 inches, is less than the spacing of the ties from center to center, 20 inches, thus differing from the old practice in which the length of the splice bars was always greater than the distance between tie centers, the length of the bars running from 24 inches up.

Following is a table showing the relation of my splice bars to those commonly employed heretofore with a 100 pound rail.

Type.	Section modulus.		Length.	Ratio of length to lower section modulus.	Weight of two bars.
	Above neutral axis.	Below neutral axis.			
Bonzano.....	11.73	9.45	26.5"	2.8	74.5 lbs.
Mine.....	9.19	12.5	15.0	1.2	55.0
Plain (old type)	7.28	7.72	24.0	3.1	68.34
100 lb. fail.....	13.71	15.91	-----	-----	-----

From the foregoing it will be seen that the proportions of my splice bars are radically different from those heretofore used and that a great saving in weight is achieved. My bars are so much shorter and have so much larger lower section moduli that the ratio of length to the lower section modulus is only 1.2 as compared with 2.8 and 3.1 of the old type bars. The length of my bars is only a little over two and one-half times the height of the rail, while with the old type the length of bars was between four and five times the height of the rail. Another noticeable distinction is in the ratio of the lower section modulus of the bars to that of the rail. The combined lower section moduli of my bars is 25 (2x12.5) which is over one and one-half times the lower section modulus of the rail, while with the other types, the combined

lower section moduli of the bars is only equal to or slightly greater than that of the rail. The relatively large lower section modulus of my bars is due to the laterally extending flanges 4 which also give the bars great resistance against lateral bending. This is important as I find that failure of splice bars is largely due to this cause, incident to the wedging effect exerted on the bars by the rails when the rails are bent downward. 75

What I claim is:

1. The combination with a track comprising rails placed end to end and ties extending transversely of the rails, with the joints between the rails located without regard to the positions of the ties, of pairs of splice bars bolted to the opposite sides of the rails of uniform cross section from end to end and lying entirely above the ties, the length of the bars being substantially no greater than the average spacing of the ties from center to center, and having a combined section modulus below their neutral axes at least one and one-third times the section modulus of the rails below their neutral axes.

2. The combination with a track comprising rails placed end to end and ties extending transversely of the rails, with the joints between the rails located without regard to the positions of the ties, of pairs of splice bars bolted to the opposite sides of the rails of uniform cross section from end to end and lying entirely above the ties, the length of the bars being between two (2) and three and one-half ($3\frac{1}{2}$) times the height of the rail and having a combined section modulus below their neutral axes at least one and one-third times the section modulus of the rails below their neutral axes. 95 100 105

3. The combination with a track comprising rails placed end to end and ties extending transversely of the rails, with the joints between the rails located without regard to the position of the ties, of pairs of splice bars bolted to the opposite sides of the rails of uniform cross section and lying entirely above the ties, the said bars having a length in inches less than twice the section modulus of one of the bars below its neutral axis, and having a combined section modulus below their neutral axes at least one and one-third times the section modulus of the rails below their neutral axes. 110 115

4. The combination with a track comprising rails placed end to end and ties extending transversely of the rails, with the joints between the rails located without regard to the positions of the ties and lying entirely above the ties, of pairs of splice bars bolted to the opposite sides of the rails, in which the length of the bars in inches is less than twice the section modulus of one of the bars below its neutral axis and in which the length of the bars is between two (2) and 139

three and one-half ($3\frac{1}{2}$) times the height of the rails and in which the combined section modulus of the two bars below their neutral axes is at least one and one-third times the section modulus of the rails below their neutral axes.

5. In combination with a pair of abutting rails, of a connection therefor comprising a pair of splice bars rigidly secured to opposite sides of the rails and lying above the plane of the bottom surface of the rails, and having a length in inches which is less than twice the maximum section modulus of one of the bars.
- 10 6. In combination with a pair of abutting rails, of a connection therefor comprising a pair of splice bars of substantially uniform cross section rigidly secured to opposite

sides of the rails and lying above the plane of the bottom surface of the rails, 20 and having a length in inches which is less than twice the maximum section modulus of one of the bars.

7. In combination with a pair of abutting rails, of a connection therefor comprising a pair of splice bars rigidly secured to opposite sides of the rails, and having a length in inches which is less than twice the maximum section modulus of one of the bars, the length of the bars being between two (2) 25 and three and one-half ($3\frac{1}{2}$) times the height of the rails, and having a combined maximum section modulus at least one and one-third times the maximum section modulus of the rails.

CHARLES D. YOUNG.
